APPARATUS FOR PRODUCING SAND CORES
AND THE LIKE

Robert R. Snow, St. Catharines, Ontario, Canada,
assignor to General Motors Corporation, Detroit, Mich., a corporation of Delaware

Application April 26, 1946, Serial No. 665,231

7 Claims. (Cl. 22—10)

1

This invention relates to an apparatus for producing sand cores and the like.

Among the objects of the invention are the following: to provide improvements in apparatus for producing cores and the like; to provide improvements in core making apparatus and the like wherein the operations are largely automatic; to provide improvements in apparatus for producing cores and the like whereby there is a saving of labor and whereby heavy labor commonly associated with core making has been largely, if not entirely, eliminated; to provide improvements in core making apparatus whereby cores can be more accurately formed on account of being automatically drawn by the apparatus, thus eliminating human inaccuracies; and to provide improvements in core making apparatus whereby the core boxes are quickly interchangeable. Other objects and advantages of the invention will become more apparent as the description proceeds.

The accompanying drawings forming a portion of this specification illustrate a machine in accordance with one embodiment of the invention.

In the drawings:

Figure 1 is an elevational view of the machine.

Figure 2 is a diagrammatic view showing the relative position of certain parts of the machine at one point in a cycle of operation.

Figure 3 is a view illustrating the means for intermittently rotating the turntable of the machine and for actuating control cam means.

Figure 4 is a diagrammatic showing of one form of hydraulic control system or circuit and illustrating the manner in which the several operations are hydraulically operated and controlled.

Fig. 5 is a somewhat diagrammatic view showing one form of means for rotating a core box part carried by the turntable of the machine.

Figure 6 is a diagrammatic view illustrating a magnetic means and control system for picking up a core box top from one position and moving the same to another position.

Figure 7 is a view with parts broken away and parts in section illustrating an "evener" device.

General description

The embodiment of the invention shown in the drawings comprises a horizontal turntable supporting four pairs of arms. Each pair of arms supports a bottom half or portion of a core box, the bottom portion of a core box being mounted so that it can be turned 180° at certain points in the cycle of operation of the machine. The

turntable and arms are driven by an electric motor and speed reducing means mounted in the base of the machine. The turntable is so controlled that it rotates 90° at a time and indexes accurately into any one of four positions. At one station (hereinafter considered as the first station or station No. 1) a core box top is raised automatically from the turntable, moved in a horizontal plane to a position over the lower half of the core box carried by the arms and finally lowered into position on the bottom half of the empty core box. At the same time a core box top is being removed from a filled core box at a station 180° from the first station, then moved in a horizontal plane above the turntable and then lowered into a position on the turntable. The core box top removed from the filled core box then moves with the turntable until it is in position at station No. 1 where it is in position to be picked up and placed on the bottom of the core box.

The means for raising, lowering and moving the upper parts of the core boxes comprises electromagnets and hydraulically operated means which raise and lower the magnets and which move the magnets in a horizontal plane when they are in their raised positions.

The station spaced 180° from the first may be considered as station No. 3 as there is a station 90° from station No. 1 at which the core box is filled with core sand by a core blowing machine. The core blowing station may be considered as station No. 2. After the upper half of the core box is removed from the lower half at station No. 3 the operator places a core drier over the sand core and fastens it in place to the lower half of the core box. The turntable then rotates 90° to station No. 4 where the core is drawn. During rotation of the turntable from station No. 3 to station No. 4, the lower half of the core box, with the core and the core drier, is caused to revolve 180° on its horizontal axis, thus turning it upside down. With the turntable stationary at station No. 4, a hydraulic piston raises a plate or table under the core drier and core. The plate carries an "evener" device which is operated automatically by air pressure. The purpose of the evener is to ensure that the pressure on the core drier is uniform at all points of contact, to compensate for any irregularities in the shapes of the various core driers and to produce a core drawing operation at right angles to the parting line. The turntable then automatically moves 90° to station No. 1 and during its movement the lower half of the core box revolves 180° on its

horizontal axis, thus turning it right side up. When at this station the bottom half has its top half placed thereon as previously described.

Detailed description

The embodiment of the invention shown in the drawings comprises an apparatus for producing sand cores and the like for use in foundry operations. Referring to Figure 1 of the drawings 10 is a housing above which is a turntable 12 having four pairs of arms 14, each pair being 90° from the next adjacent pairs (see also Figure 2). Each pair of arms adjacent its outer ends has the bottom half 16 of a core box carried thereby and so mounted that the same can be turned 180° on a horizontal axis. The core box tops are indicated by 17. Above the turntable is a slidable member 18 carrying at each end similar electromagnets 20 and electrical and hydraulic devices for actuating the same. Slide 18 is moved in a horizontal plane by means of a hydraulic cylinder 22, piston 24 (see Figure 4) and rod 26. The cylinder 22 is fixed to a stationary support 23, which in turn is carried by the upper portion of a stationary post indicated generally by 25. The magnets 20 are actuated in a vertical direction by means of similar hydraulic cylinders 28, pistons 30 (see Figure 4) and piston rods 32. The cylinders 28 and associated parts are carried by the slide 18. In Figure 1 the slide 18 is shown in its right hand position and the magnets are shown in lowered positions contacting the upper halves 17 of the core boxes at stations 1 and 3. As soon as the electromagnet at station 3 has removed the core box top from the filled core box, the operator places a core drier over the core sand and fastens it in place to the lower half of the core box by clamps.

In order to properly handle the upper half of the core box by the electromagnet, it is necessary to have the body of the box made of non-magnetic material (aluminum) to the top of which is fastened a flat steel plate to be attracted by the magnet when energized.

At the right hand side of the housing 10 (Figure 1) is shown a means for locking or holding the turntable in any one of its four indexed positions. Fixed to the turntable at 90° intervals are brackets 31 having V-notches 32 (Figure 4) formed therein. Fixed to the housing 10 is a bracket 34 supporting a hydraulic cylinder 36 which actuates a piston 37 (Figure 4) and piston rod 38 connected to a dog 40 which is moved into the V-notch to secure the turntable in indexed position.

The core drawing means (Figures 1, 4, and 7) comprises a plate or table 42 which is supported on a piston rod 43 and during vertical movement is guided by two vertical rods 44. The piston rod 43 is connected at its opposite end to a piston 46 in a cylinder 48 and is caused to move up and down by the pressure of oil or other suitable fluid in the cylinder. Mounted on the plate 42 is an air cylinder 50 which is supplied by air pressure through a flexible hose 52. The air is regulated by a control valve 53 operated by a solenoid 54. The solenoid is energized by limit switch 65 actuated by an adjustable screw 66 movable with the table 42. In the air cylinder 50 are two pistons 55 free to move horizontally and by means of piston rods 56 apply pressure against the hubs 58 of four leveling fingers represented generally by 60 (Figures 1, 4 and 7). Each leveling finger also includes an arm portion 57 connecting the hub portion 58 with a portion 60' of a leveling

finger adapted to contact the core drier. Between the hubs of the leveling fingers are similar fiber washers 62. Each piston rod 56 has a portion 59 at its end away from its piston 55 of smaller diameter than the portion adjacent its piston, thus forming a shoulder at the junction between the two portions. Between each shoulder and the adjacent fiber washer 62 is a washer 61 of stepped shape in cross section. The portion 59 of each piston rod passes through a washer 61, two fiber washers 62, and the hub portions 58 of two leveling fingers. Thus the leveling fingers are pivoted about the portions 59 of the piston rods. Stops 63 are fixed to the plate 42. The leveling fingers are biased in upward position by means of springs 64 which have one end of each in contact with the plate 42 and the opposite end of each contacting the underneath portion of the free end of a leveling finger away from its hub 20 which is pivoted on a piston rod portion 59. The operation of the core drawing means is as follows: Oil under pressure is admitted to the cylinder 48 which raises the plate on table 42 and parts carried thereby under the core to be drawn. 25 The leveling fingers make contact with the bottom of the core drier 15 (Figure 1) and adjust themselves by pivotal movement of their hubs on the piston rod portions 59. This compresses each spring 64 slightly. Air is now admitted to the air cylinder 50, the pistons 55 therein are forced outwardly a small distance. This outward movement of the pistons causes corresponding movement of the piston rods 56 so that the shoulders formed thereon force the washers 61, 62 and hubs 35 58 outwardly and tightly clamp or squeeze the same between the shoulder and stops 63, thereby holding the fingers in position. In other words the squeezing action applies pressure to the sides of the hubs 58 and washers whereby frictional 40 forces therebetween hold the fingers against pivotal movement on the smaller diameter portions 59 of the piston rods. Latches holding together the core dried and inverted bottom part of the core box are tripped open and oil pressure 45 is removed from cylinder 48, allowing the plate or table 42 to move down carrying the core drier and core with it to a position from which they may be removed by the operator. The core drier and core may now be placed in an oven for baking 50 the core.

During movement of the turntable from station 3 to station 4 the bottom half of the core box and the core drier fixed thereto are rotated 180° to invert the same. During movement of the turntable from station 4 to station 1 the inverted bottom half of the core box is rotated 180° to again bring the same into its right side up position so that the top half of the core box can be placed thereon at station 1.

The means for rotating the bottom portion of the core box, etc., as just described, is illustrated in Figures 1 and 5. Carried by the turntable is an electric motor 70 connected to a gear pump 72. The inlet side of the pump is connected by pipe 74 to an oil supply tank 76. The outlet side 78 of the gear pump leads to a volume control 80 and then to a four-way valve 82 having an actuating element 79. The actuating element of the four-way valve is operated by a stationary cam 84 mounted above the turntable, said cam being fixed to post 25. Oil, controlled by the valve 82, enters a cylinder 86 carried by the turntable causing a piston 88 to move a chain 90 turning sprocket 91 is fixed to a shaft 89 which, in turn, 95 is fixed to the bottom of a core box. The move-

ment of the piston 86 is just sufficient to rotate 180° the bottom of the core box with the core drier clamped thereto. The foregoing action takes place while the turntable is moving from station 3 to station 4. When the cam 84 disengages the actuating element 79 of the valve 82 (by movement with the turntable of the valve 82 and its adjusting element 79 past the cam) the oil pressure is reversed in cylinder 86 thereby moving piston 88 in the reverse direction and causing the return of the bottom of the core box to its original right side up position. This action takes place while the turntable is rotating from station No. 4 to station 1.

After the turntable has moved to station No. 1 and a core box top applied thereto as previously described, the now closed core box is moved to station No. 2 where the core sand mixture is blown into the core box by a core blowing machine of any conventional design automatically controlled by operation of the core making machine.

In Figure 3 is illustrated a means whereby the turntable may be actuated, the mechanism shown being located in the housing 10. An electric motor 96 rotating at constant speed drives a rotating disc 98 at a constant speed. A suitable variable speed means 99 and speed reducing device 100 reduce the speed of the rotating disc greatly as compared with that of the electric motor. For each revolution of the disc 98 the turntable 12 is indexed 90° by means of a ratchet clutch 102 which drives the turntable shaft 104. In Figure 3 is shown a camshaft 106 which rotates continuously at constant speed. The camshaft is driven by the electric motor and speed reducing means by means of a chain or belt 107. To the camshaft are fixed a plurality of control cams for operating various hydraulic controls, one of these cams 108 being shown in Figure 3.

Figure 4 shows what may be considered as the main hydraulic system and illustrates the manner in which various parts of the machine are operated or controlled. An electric motor 120 is directly connected to a gear pump 122. Oil from a tank 124 is fed under pressure by means of the pump to a high pressure header 126. Pressure is adjusted by a relief valve 128 in the line 129 leading from the pump to the header. Oil is returned to the tank 124 by means of a return header 130. In Figure 4 are shown cams 108, 109, 110, 111, 112 and 113 which control various hydraulic circuits. It will be understood that the cams 108 to 113 inclusive are rotated by the camshaft 106 which rotates continuously when the machine is being operated.

Cam 108 operates a pilot valve 132 which causes a four-way valve 134 to allow oil under pressure to enter one end of cylinder 22 (see also Figure 1), to thereby move the piston 24 in one direction. This causes the slide 18 and two magnets 20 carried thereby to traverse to one end of the stroke. Further rotation of the cam 108 causes reverse operations of the pilot valve 132, four-way valve 134 and piston 24. This causes the slide and magnets to traverse to the opposite end of the stroke. A volume control 136 is provided in the line leading from the high pressure header 126 to the four-way valve 134 to regulate the speed at which piston 24 travels. Oil line 137 leads from the four-way valve 134 to the return header 130.

Cam 109 actuates a pilot valve 140 which controls a four-way valve 142 which in turn allows oil under pressure to enter one end of hydraulic

cylinders 28 (see also Figure 1). These cylinders operate in parallel. Oil pressure in the cylinders 28 cause the pistons 30 therein to move in one direction to simultaneously raise the two magnets

20. Further rotation of the cam 109 reverses the operation of the four-way valve 142 to move the pistons 30 in the opposite direction in cylinders 28 to lower the magnets simultaneously. A volume control 144 is provided in the line leading from the header 126 to the four-way valve 142 to regulate the speed of travel of pistons 30 in cylinders 28. Oil is returned to the header 130 from the four-way valve 142 by oil line 145.

Cam 110 actuates a four-way valve 148 which controls flow of oil under pressure from header 126 to the opposite sides of piston 150 in hydraulic cylinder 152. Movement of the piston 150 operates air valve 154 on the core blowing machine 156. Oil line 157 leads from the valve 148 to return header 130.

Rotation of cam 111 actuates a four-way valve 158 which causes oil under pressure to enter cylinder 36 to thereby move the piston 37 therein in one direction to move the dog 40 into the V-notch 32 and thereby hold the turntable 12 in indexed position. Oil under pressure also flows into one end of a cylinder 160 to move a piston 162 therein to apply a brake 164 to the turntable driving shaft. Further operation of cam 111 causes reverse operations of the four-way valve and pistons 37 and 162 to release the dog 40 from the V-notch 32 and to release the brake. By means of line 165 oil is returned to header 130 for return to tank 124.

Cam 112 actuates a four-way valve 168 which causes oil under pressure from header 126 to enter one end of a cylinder 170 and move piston 172 therein in one direction to move the hopper 174 of the core blower to operating position

40 at station No. 2. Further rotation reverses the operation of the four-way valve and piston 172 to thereby move the core blower hopper to inoperative position away from the turntable. Oil line 175 leads from the valve 168 to the return header 130.

Rotation of cam 113 operates a four-way valve 176 which causes oil under pressure to enter one end of cylinder 48 to raise the piston 46 therein and plate 42 of the core drawing mechanism at station 4. Further rotation of cam 113 causes reverse operation of the four-way valve 176 and piston 46 to lower the core drawing mechanism. A volume control 178 is provided in the line leading from the header to regulate the speed of the piston 46. Oil is returned by pipe 179 from the four-way valve 176 to the return header 130.

The electric circuit for one of the magnets is illustrated diagrammatically in Figure 6. The circuit for the other magnet is the same as that illustrated in Figure 6. For lifting the top halves of the core boxes the magnets are energized by current flowing in one direction through the magnet coils. To release the top halves of the core boxes reverse current is temporarily passed through the magnet coils to destroy residual magnetism. In the position shown in Figure 6 the magnet 20 is in elevated position above the core box. Upon downward movement of the magnet, by means of the hydraulic cylinder 28, piston 30 and rod 32, the limit switches 228 and 229 are actuated causing 228 to close and 229 to open. Switches 228 and 229 are mounted on each end of the magnet and are caused to operate by mechanical contact with the top of the core box. At this time switches 230 and 231 are

in their normally closed positions. A circuit is then established from L1, connections 239, 240, 242, switch 231, connection 244, switch 228, connection 246, switch 230, connection 248, and then by parallel circuits through the coils of contactor CR1 and time relay TR1 to L2. The circuit from 248 through the coil of CR1 is by connector 250, coil 252 of CR1, and connector 254 to L2. The circuit from 248 through the coil of TR1 is by means of connector 256, coil 258 of TR1, and connector 260 to L2.

Energization of coil 253 of TR1 actuates an arm 259 carrying blade 261 which closes contact 227. Energization of the coil 252 of CR1 raises an arm 262 carrying blades 264, 266, and 268, which close contacts 221, 223 and 232 respectively. This energizes the magnet 20 by means of the circuit from L1, contact 221 closed by blade 264, connector 270, magnet coil 222, connector 272, contacts 223 closed by blade 266, and then to L2. The hydraulic cylinders then lift the magnets and core box tops. There is mechanical lag which allows the limit switches 228 and 229 to return to normal positions (switch 228 open and 229 closed) before the core box top is moved. A circuit is then established from L1 through connector 239, conductor 240, switch 229, connectors 276 and 278 to contact 232 closed by blade 268, connector 280, coil 252 and connector 254 to L2. A circuit is also established from 249 by means of connector 242, switch 231 and connector 244 to connector 278. Circuit portions 250 and 256, coil 258 of TR1, and connector 260 to L2 are in parallel circuit relation with the corresponding circuit through the coil 252 of CR1. The foregoing circuit holds while the magnet and top half of the core boxes are lifted full height by hydraulic cylinder 28 and traversed to the opposite end of the horizontal traverse of slide 18 by hydraulic cylinder 22. At this time limit switches 230 and 231 are opened by member 233 carried by the slide. Circuit from L1 to L2 is then from 239, 240, 229, 276, 278, contact 232 closed by 268, 280, and then through the coils of CR1 and TR1 in parallel to L2.

The magnet 20 is then lowered to set the top half of the core box on the turntable or onto an empty lower half of a core box, as the case may be. When the mechanical slack is taken up the limit switch 228 is closed and 229 is opened. Opening of 229 (since 231 has been opened previously as described) cuts off current from coil 252 of CR1 and coil 258 of TR1, thus deenergizing the same. Although coil 258 of TR1 is now deenergized the blade 261 still closes contact 227 for a period of about two seconds. Deenergizing coil 252 of CR1 causes blades 264 and 266 to drop down closing back contacts 225 and 224 respectively. A demagnetizing circuit is then set up through the coil 222 of the magnet 20. This circuit is from L1 through 239, back contact 224, connection 272, magnetizing coil 222, connector 270, back contact 225 (closed by 264), connector 290, current limiting resistor 226, contact 227 still closed by 261, and connector 260 to L2. At the end of about two seconds the blade 261 of time delay relay opens contact 227 to open the demagnetizing circuit. Any suitable means such as a dash pot or other means may be employed to obtain the time delay. The magnet 20 is then raised by hydraulic power which opens 228 and closes 229. No closed circuit will be set up however as 230 is in the open position and auxiliary contact 232 is open.

From the foregoing detailed description of an

apparatus constructed in accordance with a specific embodiment of my invention it will be apparent that I have provided a core making machine adapted for automatic operation and at adjustable speed so that the operation can be timed to suit the cores being produced. Also provided is a power driven, accurately indexed, and automatically operated turntable. The machine further includes automatic means for turning over the core box containing a core, automatic means for blowing the core and automatic means for drawing the core.

It will be understood that various changes and modifications in the specific embodiment of the invention described in detail herein, may be made without departing from the spirit and principles of my invention and I do not intend to limit the patent granted for my invention except as necessitated by the prior art.

I claim:

1. In apparatus of the class described, a turntable, a plurality of core boxes carried by the turntable, means for rotating the turntable to a plurality of stations, one of said stations being a core box top removing station and a diametrically opposite station being a core box top replacing station, a slideable member above the turntable movable horizontally back and forth in the vertical plane through the axis of the turntable and said core box top removing and replacing stations, an electromagnet at each end of the slideable member, hydraulically operated means for moving the slide and electromagnets in a horizontal plane above the turntable, hydraulically operated means carried by the slide to move the two electromagnets in unison in a vertical direction while the slide is at each end of its path of travel, means for energizing the electromagnets to pick up core box tops when the slide is at one end of its travel and after lowering of said electromagnets into contact with said core box tops, means for maintaining the energization of said electromagnets while the electromagnets are raised, while they are moved by said slide to the opposite end of its path of travel and while they lower the core box tops carried thereby, and means for deenergizing the electromagnets to release the core box tops after the electromagnets have been lowered at said opposite end of the path of travel of said slide.

2. In apparatus of the class described, a turntable, a plurality of core boxes carried by the turntable, means for intermittently rotating the turntable to a plurality of stations, one of said stations being a core box top removing station and a diametrically opposite station being a core box top replacing station, a slideable member above the turntable movable horizontally back and forth in the vertical plane through the axis of the turntable and said core box top removing and replacing stations, an electromagnet at each end of the slideable member, hydraulically operated means for moving the slide and electromagnets in a horizontal plane above the turntable, hydraulically operated means carried by the slide to move vertically the two electromagnets in unison, automatic means for energizing the electromagnets to pick up core box tops when the slide is at one end of its travel and after lowering of said electromagnets, for maintaining the energization of said electromagnets while the electromagnets are raised, while the electromagnets and core box tops are moved by the slide to the opposite end of its path of travel and while the electromagnets are lowered and for

deenergizing the magnets to release the core box tops after the electromagnets have been lowered at said opposite end of the path of travel of said slide, and hydraulically operated means for locking the turntable in a stationary position during movement of the slide and electromagnets.

3. In an automatic core making machine having a core blowing station, a core drawing station, a core box top removing station and a core box top replacing station; a turntable; a core box carried by the turntable; mechanism for rotating the turntable to said plurality of stations; mechanism for placing a core box top on the bottom of a core box at one of said stations consisting of a horizontally movable slide above the turntable and a vertically movable device carried by the slide adapted to raise a core box top from the turntable when the horizontally movable slide is in one position of movement and to place the same on the bottom of a core box when the slide is at another position of movement; mechanism at another station beyond said core blowing station for automatically removing a core box top from a filled core box, moving said removed core box top in a horizontal plane above said turntable and then placing the same on the turntable at a point radially inward of the bottom of the core box from which the top was removed, and control means for sequentially actuating said mechanisms at said stations.

4. In apparatus of the class described, a turntable, four core boxes carried by the turntable at 90° intervals, automatically operated mechanism for rotating the turntable sequentially to four stations at 90° intervals, the first station being a station at which a core box top is placed on a core box bottom, the second a core blowing station, the third a core box top removing station and the fourth a core drawing station, a horizontally movable slide above the turntable in the vertical plane through the axis of the turntable and stations one and three, and vertically movable mechanism at each end of the slide to pick up a core box top from a filled core box on the turntable at station number three at the same time that a previously removed core box top is being picked up from the turntable at station number one and while the slide is at one end of its path of travel, said vertically movable mechanism placing the core box top picked up from the filled core box at station number three onto the turntable and placing the core box top picked up from the turntable at station number one onto a core box bottom when the slide is at the other end of its path of travel.

5. In an apparatus of the class described, a turntable, four core boxes carried by the turntable at 90° intervals, automatically operated mechanism for intermittently rotating the turntable 90° at a time to four stations with a core box at each station, the first station being a station at which a core box top is placed on a core box bottom, the second a core blowing station, the third a core box top removing station and the fourth a core drawing station, a member above the turntable slidable horizontally back and forth in the vertical plane through the axis of the turntable and stations one and three, a first cylinder and fluid pressure actuated piston for moving said slidable member back and forth, a cylinder carried at each end of said slidable member, a fluid pressure actuated piston in each cylinder at each end of the slide and movable in a vertical direction, an electromagnet movable by each vertically movable piston, fluid

pressure connections to said first cylinder for actuating the piston therein to move the slidable member back and forth, fluid pressure connections to each of the cylinders carried at the

5 ends of the slidable member to move the pistons therein and the two electromagnets in unison in a vertical direction when the slide is at each end of its path of travel to sequentially raise and lower the two electromagnets, and electrical circuits to energize the two electromagnets when they are lowered onto the two core box tops on the turntable at stations one and three, to maintain the energization of the two electromagnets while the two vertically moving pistons

10 are moving upwardly, while the slide is moving to the other end of its path of travel and while the vertically moving pistons are being lowered, and then to deenergize the two electromagnets to thereby release the two core box tops, one of

20 them being released on a core box bottom at the first station and the other being released onto the turntable at the third station at a point radially inward of a filled core box.

6. In an apparatus of the class described, a turntable, four core boxes carried by the turntable at 90° intervals, a continuously rotating member, mechanism actuated by the continuously rotating member for intermittently rotating the turntable 90° at a time to four stations with

30 a core box at each station, the first station being a station at which a core box top is placed on a core box bottom, the second a core blowing station, the third a core box top removing station and the fourth a core drawing station, a

35 member above the turntable slidable horizontally back and forth in the vertical plane through the axis of the turntable and stations one and three, a first cylinder and fluid pressure actuated piston for moving said slidable member back-and-forth, a cylinder carried at each end of said slidable member, a fluid pressure actuated piston in each of the cylinders at the ends of the slidable member and movable in a vertical direction, an electromagnet movable vertically by each vertically

40 movable piston, means for admitting fluid pressure to said first cylinder for actuating the piston therein to move the slidable member back and forth, means for admitting fluid pressure to each of the two cylinders at the ends of the slidable member to move the pistons therein and the two electromagnets in unison in a vertical direction when the slide is at each end of its path of travel to sequentially raise and lower the two electromagnets, electrical circuits to energize the

45 two electromagnets when they are lowered onto the two core box tops, to maintain the energization of said two electromagnets while the two vertically moving pistons are moving upwardly, while the slide is moving to the other end of its path of travel and while the vertically moving pistons are lowered and then to deenergize the two electromagnets, and means controlled by

50 said continuously rotating member for sequentially operating said slide and parts carried thereby.

7. In an automatic core making machine having a core blowing station, a core drawing station, a core box top removing station and a core box top replacing station; a turntable; a plurality of core boxes carried by the turntable; a continuously operating member; means actuated by the continuously operating member for intermittently rotating the turntable to said plurality of stations; means at one of said stations for re-

75 moving a core box top from a filled core box,

moving it radially inward and placing it on the turntable; means at another station for picking up from the turntable a previously removed core box top, moving it radially outward of the turntable and placing it on the bottom of a core box bottom during the same time interval that a core box top is being removed, moved radially inward and placed on the turntable; means for inverting the bottom of the core box while the turntable is moving from the station at which the top is removed to the core drawing station and for reinverting the same while the turntable is moving from the core drawing station to the station at which the core box top is placed on the bottom part; means controlled by said continuously operating member for automatically operating said means for picking up a core box top, moving it radially outward and placing it on a core box bottom and for simultaneously therewith actuating the means for removing a core box top from a filled core box, moving it radially inward and placing it on the turntable; and means controlled by movement of the turntable for actuating said means for inverting and reinverting the bottom of a core box.

ROBERT R. SNOW.
